UNITED STATES PATENT OFFICE.

ANDREW R. RIDDERSTROM, OF NAHANT, MASSACHUSETTS, ASSIGNOR TO BEACON FOLDING MACHINE COMPANY, OF LYNN, MASSACHUSETTS, A CORPORATION OF MASSACHUSETTS.

FOLDING MACHINE AND METHOD.

Continuation in part of application Serial No. 407,336, filed September 1, 1920, and Serial No. 480,177, filed June 24, 1921. This application filed February 28, 1923. Serial No. 621,952.

To all whom it may concern:

Be it known that I, ANDREW R. RIDDERSTROM, a citizen of the United States, and a resident of Nahant, in the county of Essex and Commonwealth of Massachusetts, have invented new and useful Improvements in Folding Machines and Methods, of which the following is a specification.

The present application is a continuation 10 of applications Serial Nos. 407,336, filed September 1, 1920, and 480,177, filed June 24, 1921.

The present invention relates to folding methods and machines, and more particularly to methods of and machines for folding a binding strip around the edge of a boot or shoe upper to which it is attached.

The binding strip is usually sewed upon a face of the upper along an edge thereof, 20 after which the strip is folded around the said edge and into even contact with the opposite face. In order that the binding strip, after folding, may lie evenly and smoothly against the said opposite face, it is necessary that the strip be first wiped tightly 25 across the edge to which it is secured and then pulled and held tightly during the folding operation and while it is pressed against the said opposite face; and it is necessary also that the strip be folded exactly 30 at the proper points or lines, and not to one side thereof. This is very difficult of achievement even by hand, and no successful mechanical means for operating upon 35 shoe-upper binding strips have heretofore been devised. Binding strips are therefore still folded laboriously, clumsily and unsatisfactorily by hand, the various operations being performed separately at different 40 times, wasting much time and adding greatly to the cost.

It is an object of the present invention, accordingly, to improve upon present-day methods of folding binding strips, reducing 45 the cost of manufacture and yielding a better and more satisfactory product.

To this end, a feature of the invention contemplates first wiping a portion of the strip, and then advancing or feeding it to a 50 plow, which folds the wiped portion of the strip. This operation is continued step by step, the wiping and the folding being pref-

erably performed during successive pauses of an intermittent step-by-step feed. The wiping action is effected by a wiper that acts preferably at a point directly opposite to the point of action of a retainer. The folded portions of the strip are successively pressed into even contact with the other face of the sheet. It is well to grip the portions of the strip tightly and to pull them tight until they have become pressed.

Another object of the present invention is to provide an improved wiper operable intermittently at spaced portions only of the strip, and in a direction rearwardly oblique or diagonal to the strip. The preferred wiper operates not merely in the plane of the stock, but at an angle to the said plane. This angular movement results in a more efficient wiping action than is obtainable from wipers operating in the plane of the stock.

In the preferred machine described and illustrated herein, this object is attained 75 through the use of a rotary wiper that is mounted upon a crank stem disposed at an angle to its operating shaft. By the very nature of its construction, furthermore, the wiper may be mounted very close to the fold 80 presser. The tendency of the fold presser, that would otherwise exist, to pull the convex portions of the leather out of range of action of the wiper, is thereby reduced to a considerable extent, with the consequent result 85 that the portions of the binding strip sewed at convex portions of the leather are wiped as efficiently as those sewed at other portions of the leather. A very satisfactory and a uniform wiping action is thus obtained.

The binding strip is usually coated with a layer of cement to cause it to stick to the leather after it has been pressed down by the fold presser. There is a tendency for 95 the cemented face of the binding strip to stick to the edge of the leather when accidentally brought into contact therewith, preventing the binding strip being laid evenly and smoothly against the face of the 100 leather and causing bunching and other irregularities.

A further object of the invention, therefore, is to prevent the cemented face of the

binding strip contacting with the edge of the leather before it is laid properly in position, thereby assuring its being laid evenly and smoothly. This end is achieved, in the 5 specific embodiment of the invention that is herein illustrated and described, by means of a separator that lies in the space between the binding strip and the edge of the leather.

10 With the above and other objects in view, as will become clear in the course of the following description, the invention consists of the improved method and machine hereinafter described, illustrated in the accompanying drawings, and defined in the appended claims.

In the drawings, Fig. 1 is a view in elevation, partly in longitudinal section, upon a reduced scale, of a machine constructed 20 according to a preferred embodiment of the present invention; Fig. 2 is a plan of the forward part of the machine, the housing 212 being removed; Fig. 3 is an elevation of the forward part of the machine, also 25 with the housing 212 removed; Fig. 4 is a perspective view of the upper, forward part of the machine, parts being broken away for clearness; Figs. 5, 6 and 7 are detail plan views, showing three steps performed 30 in the preferred machine during the operation of folding a binding strip attached to a shoe upper; Figs. 8, 9 and 10 are vertical sections taken substantially upon the lines 8—8, 9—9 and 10—10 of Figs. 5, 6 and 7, 35 respectively, looking in the directions of the arrows; Fig. 10^a is a view of a detail; Fig. 11 is a longitudinal vertical section taken substantially upon the line 11—11 of Fig. 2, looking in the direction of the arrows; 40 Fig. 12 is a transverse vertical section taken substantially upon the line 12—12 of Fig. 11, looking in the direction of the arrows; Fig. 13 is a plan of the preferred wiper 45 of the present invention, and of its support; Fig. 14 is a corresponding front elevation; Figs. 15 and 16 are sectional views of a shoe upper, showing a binding strip as it usually appears when attached to a straight edge and to a concave edge of the upper respectively; Fig. 17 is a section similar to Figs. 50 15 and 16, showing the binding strip in finally folded position upon the upper; Figs. 18, 19 and 20 are front views of the preferred wiper, shown in different positions, 55 Fig. 18 showing the wiper inactive, Fig. 19 showing the wiper at the commencement of the wiping action, and Fig. 20 showing the wiper at the end of the wiping action; Figs. 21, 22 and 23 are rear views corresponding, 60 respectively, to Figs. 18, 19 and 20; and Figs. 24, 25 and 26 are plan views of the wiper and the shaft upon which it is mounted, shown in positions respectively corresponding to Figs. 18, 19 and 20.

65 The invention is illustrated in the accom-

panying drawings in connection with the folding of a binding strip 2, Figs. 15 and 16, of cloth, silk and the like, around the edge 4 of a sheet of leather or other material 6, such as a boot or shoe upper. An edge 70 8 of the binding strip is sewed to a face 10 of the shoe upper along the edge 4, so that the sheet and the strip extend at an angle to each other from the secured-together edges 4 and 8. Resulting from the manner 75 in which the sheet and the strip are sewed together, they are generally in more or less close parallelism, as shown in Fig. 15, but the angle between them may be quite large, as is illustrated in Fig. 16. The stitches 80 are shown at 12 as extending preferably through, or over and around, a reinforcing cord 14 positioned upon the other face 16 of the shoe upper, along the edge 4. It will be understood that the invention is equally applicable to other articles than that which is herein chosen for purposes of illustration, and the elements of the article need not necessarily be of the relative dimensions shown. It may be desirable, for example, 90 to fold an element of relatively large dimension over the edge of an element of relatively small dimension. For definiteness, the element that is to be folded will hereinafter be referred to in the specification and the claims as the "strip", and the element about the edge of which the strip is to be folded will be hereinafter referred to as the "sheet", "stock", "upper", "work", etc., though the adopted terminology may not 100 be strictly applicable to the specific article which may be under consideration. With this understanding, the chief object of the invention is to fold properly a "strip", such as the binding strip 2, from the position illustrated, for example, in Figs. 15 and 16, into the position illustrated in Fig. 17.

The method of the present invention may be carried out with a machine built in the main along the lines of a somewhat similar 110 machine illustrated and described in a co-pending application, Serial No. 352,987, filed January 21, 1920, and assigned to the assignee of the present application, but suitably modified. Reference is made to this 115 application and to the aforesaid applications Serial Nos. 407,336 and 480,177 for a fuller description of parts of the illustrative machine not fully described herein, because unnecessary to an understanding of 120 the present invention. The shoe upper is initially placed in the preferred machine upon a platform or support 24, Figs. 1 to 11, with the face 10 of the upper in contact with the support. The free or unsecured 125 edge 26 of the strip 2 is initially moved across and around the secured-together edges 4 and 8 into the space between an interior side face 28 of a feed point 30 and a plow 32 that stands up integrally from a 130

- plate 34. The machine being set into operation, successive portions of the unsecured edge or portion of the strip 2 are intermittently wiped tightly across the secured-together edges 4 and 8, as shown more particularly at 36, Figs. 8 to 10 and 17, by the combined action of a wiper 38 and a retainer 246 that presses down heavily at this time upon the upper directly opposite to the point of action of the wiper. It is very important to the subsequent operation that the strip be wiped very tightly. The successively wiped portions are then advanced or fed step by step by the feed point and a co-operating feed block 41 to the plow 32, by which they are initially intermittently folded around the secured-together edges 4 and 8, and they are gripped intermittently between the interior side face 28, Figs. 8 to 11, of the feed point and the upstanding plow 32, becoming thereby pulled tightly. The intermittent wiping, and folding and gripping operations are performed upon the successive portions of the strip alternately during successive pauses in the feed. The folded portions are then advanced to a fold presser 42. The fold presser successively presses down the successively formed folds into even contact with the face 16 of the sheet, as shown in Fig. 17. These operations are continued in timed relation to one another until the whole strip has become folded.
- The outer portion of the platform or support 24 is shown inclined downward, to facilitate operation upon sharply concave portions of the stock. Such portions, as is well known, tend to curl as they are opened out. The curled parts are, in the illustrated machine, permitted to bend down upon the inclined portion of the support. If the support were perfectly level, the strain of the curled portions would be communicated to the margins that are operated upon, making manipulation difficult. As shown in the drawings, the incline commences close to the operating instrumentalities of the machine, so as to permit the stock to curl close to the concave margin of the work.
- According to the preferred form of the present invention, the wiper 38 acts intermittently, at spaced or separated portions only of the strip, while the stock is held stationary, during pauses in the feed. The wiper is bodily actuated in a direction rearwardly diagonal of the strip and oblique to the plane of the leather sheet to effect a correspondingly diagonal wiping action. In Fig. 24, and also enlarged in Fig. 6, the wiper is shown in plan view before it engages the strip. It has been moving in the direction of the left-hand arrow, Fig. 24, and is shown just to the rear of a limiting line 39, Figs. 24, 25 and 26. Corresponding end and rear views are shown in Figs. 18 and 21 respectively. It then engages the strip at substantially the point where the strip is attached to the leather sheet, and moves in the direction of the arrow of Fig. 25, diagonally from the position of Fig. 6 to that of Fig. 7, towards the unsecured edge 26 of the strip. In so doing, it moves obliquely rearward from the line 39 and above a horizontal plane 29, Figs. 18 to 23, so as to bite the more firmly into the strip and wipe it the more tightly across the secured-together edges 4 and 8, as shown at 36, Figs. 8 to 10 and 17. This action of the wiper oblique to the plane of the sheet, and the wiping action oblique or diagonal to the strip, are considered to be very important features of the present invention: the former action insuring tight wiping; and the latter, by imposing less strain upon the strip than would be the case if the wiping were effected forcefully directly across or at right angles to the strip, reducing to a minimum the danger of tearing the strip. The latter danger is particularly to be guarded against because the retainer 246 is necessarily adjusted to press down very heavily upon the stock to prevent the wiper dragging the upper as a whole away from the retainer, and too strong action by the wiper in a direction at right angles to the strip is liable to result in tearing the strip and rendering it unfit for further use. The successive, active wiping portions of the wiper remain, however, at the same level, directly opposite the retainer, so that the retainer, when operating idly, can not engage the wiper and injure it.
- The wiper continues to move diagonally to the strip, from the position of Figs. 19, 22, 25 and 7, to the position of Figs. 20, 23, 26 and 5. The wiper dips at the same time below the horizontal plane 29, moving also in the direction of the arrow of Fig. 26, in preparation for its next upward oblique movement. During the return movement of the wiper, it is vertically considerably below the horizontal plane 29, so as not to engage the stock during the return movement. The cycle of operations is then resumed, the stock having meanwhile been fed forward another step. The complete diagonal rearward movement of the wiper, as seen in plan, will be understood from a study of the successively assumed positions shown in Figs. 6, 7 and 5.
- The above-described, desired operation of the wiper may be attained in many ways, as will be understood by persons skilled in the art, and all such are considered to be within the scope of the present invention, the preferred way being illustrated in Figs. 13, 14 and 18 to 26 inclusive, for the purpose of explaining a practical embodiment of the invention, as is required by the statutes. The preferred wiper is shown pro-

- vided with a cylindrical opening 40 by means of which it may be mounted over a crank stem or eccentric 31 that is mounted at the end of a rotating shaft 52 at an angle to the shaft. The shaft 52 is rotated in the direction of the arrow 27, Fig. 24, by mechanism hereinafter to be described. The wiper is retained in place upon the crank stem between an integral flange 37 and the head of a screw 43 that is screwed into position within a screw-threaded opening 44 that extends longitudinally inward from the end of the crank stem 31. It is found that the best results are obtained by so inclining and offsetting the eccentric or crank stem 31 that the stationary points 45 of the crank stem that is in line with the axis 46 of the shaft 52, at which no rotation takes place, shall be near the free end of the crank stem, as will be clear from Figs. 24, 25 and 26. It will be understood, however, that the details and the dimensions may be modified and varied without departing from the spirit and scope of the invention. The diagonal progress of the wiper is indicated by the inclination of the line 35 passing through the stationary point 45 and any given point of the wiper, as the centre of its wiping face.
- 30 The shaft 52 is mounted in a bearing 54, Figs. 2, 3, 4, 13 and 14, and is held against longitudinal movement within the bearing by the integral flange 37 on one side and a collar 47, that is secured to the shaft 52 by a pin 48, on the other. As the shaft is rotated, the obliquely disposed crank stem 31 will be moved to successive positions indicated in Figs. 24, 25 and 26, causing the wiper to be wiggled in a fashion that will be readily understood by persons skilled in the art. As the wiper is loosely mounted about the crank stem, it tends to rotate idly thereabout. To keep its active face always properly presented to the stock, therefore, it is provided with a cam shoulder 49, Figs. 18 to 23, that is adapted to ride upon or over a lug 50. The shape of the cam determines the amount by which the wiper is raised above the plane 29, and also how nearly level the successively acting wiping portions of the wiper shall be. The portions of the cam shoulder 49 between the points 51 and 53 are caused to ride back and forth over the lug 50 during the cycle of operation of the wiper, in a manner that will be clear from Figs. 21, 22 and 23, to produce the above-described wiping action.
- 35 The other or free end of the shaft 52 is provided with a ball 56 mounted in a socket 58 upon the forward end of a shaft 60. The purpose of this construction is to permit of adjusting the wiper vertically and to enable disposing the shaft 52 at an inclination, as shown in Fig. 2, so as to bring the wiper closer to the fold presser. The vertical adjustment may be effected by vertically adjusting the bracket 61, Figs. 3, 4 and 14, that carries the bearing 54 and the lug 50, through the medium of screws 63 in enlarged openings 65. The vertical adjustment may be effected without disturbing the ball-and-socket connection between the shafts 52 and 60. A screw 67 may be provided for fine-adjustment purposes. Its lower end 69, Fig. 3, is threaded into a stationary part of the frame of the machine and thereby determines the exact vertical position of the wiper. The bracket 61 may therefore be removed, if occasion should require, and it may then be replaced, the screw 67 insuring that there shall be no necessity for readjusting the position of the wiper, and the screws 63 serving to lock the bracket in the required adjusted position.
- 40 It results from this construction that the wiper is moved forward with the wiped strip, becoming positioned very close to the fold presser at the limit of its forward movement, and making it possible to operate more effectively on sharp convex curves, that would otherwise be pulled out of range of the wiper by the fold presser, if the wiper were further away from the fold presser. The wiper, on other portions of its cycle, assumes a position just opposite to the separator 143.
- 45 The shaft 60 carries a gear 62 that meshes with a gear 64 upon a driving shaft 66 that is horizontally journaled in bearings of the machine frame. The ball-and-socket connection permits the shaft 60 being inclined to the driving shaft 66, as will be understood from Figs. 2 and 3. By means of this construction, the wiper is rotated from the driving shaft through the medium of a pin-and-slot relationship between the ball and the socket elements of the ball-and-socket connection. To time the movement of the wiper with respect to the other operating instrumentalities of the machine, provision is made for adjusting the meshing engagement of the gears 62 and 64. The adjustment may be effected by unscrewing screws 69 to loosen a bracket 71 within which the end 73 of the shaft 60 is journaled. The shaft 60 may then be angularly adjusted to the extent of one tooth or more and the bracket 71 may then be returned to its normal position and resecured in place by the screws 69.
- 50 To drive the driving shaft, it is provided with a hand-and-balance wheel 68, Fig. 1, having a clutch face 70 that is adapted to be frictionally engaged by a clutch face 72 of a loose driving cone pulley 74. The cone pulley is normally separated from the hand-and-balance wheel by a spring 76, but may be actuated toward the latter, to effect frictional engagement of the clutch faces, by a bell-crank lever 78 pivoted at 80 and oper-

able through a treadle or other manually controlled device (not shown) that is connected to the bell-crank lever by a link 82. According as the treadle is depressed more or less, the clutch faces will engage more or less firmly, thus providing for varying the speed of rotation of the driving shaft 66. Upon the release of the treadle, the bell-crank lever will be returned to its illustrated, ineffective position by a compression spring 84 mounted upon a rod 86 that is pivotally mounted at its lower end in an abutment 88. The spring 76 will at the same time separate the clutch faces 70 and 72, and a brake 90, that is also pivoted at 80, will be acted upon at 193 by an adjustable member 92 that it carried by the bell-crank lever to stop the rotative movement of the hand-and-balance wheel 68 and, therefore, 20 of the driving shaft 66.

The feeding mechanism, comprising a feed block 41 and a feed point 30, as has already been mentioned, is also driven from the driving shaft 66. The feed block 41, 25 Fig. 11, is shown carried integrally with the plow 32 upon the plate 34. The plate 34 is mounted upon a holder 93 that is secured as by a set screw (not shown), to a rocking support 94. The rocking support is 30 pivotally mounted about a rod 96 that is secured to the frame of the machine by a screw 98. The rocking support 94 is provided with a diagonally disposed cylindrical opening 100, Figs. 11 and 12, within 35 which is slidably mounted a diagonally cylindrical block 102 the upper flat face of which is substantially horizontal, as shown at 104. The angle of inclination of the opening 100 is preferably in the neighborhood of 40 thirty degrees. The cylindrical block 102 is adapted to be actuated by an eccentric or crank pin 106 of the driving shaft 66. The eccentric or crank pin is rotatably mounted in the block 102 and extends through an 45 opening 108 of the rocking support 94. Rotative movement of the shaft 66 will be converted by the eccentric into combined sliding and oscillating or rotative movement of the block 102 and this, in turn, will effect 50 a rocking movement of the rocking support about the rod 96.

The feed point 30 is pivotally mounted at 110 upon the rocking support 94 so as to be rocked therewith and with the lower feed block 41, and is normally maintained in contact with the feed block by a leaf spring 112 one end 114 of which is secured to the frame of the machine, as shown in Fig. 1, and the other end 116 (Fig. 11) of which 55 presses down upon the body portion 118 of the feed point. The body portion 118 is slotted, as shown in Fig. 12, and a screw post 120 is adjustably clamped between the side walls of the slot by a screw 122, Fig. 11. 60 The upper face 104 of the block 102 is

adapted to engage the post 120, thereby to raise the feed point 30, in opposition to the pressure of the spring 112.

As the driving shaft 66 is rotated, the rocking support 94 is rocked from right to 70 left and from left to right, as viewed in Fig. 12, imparting an oscillating movement to the lower feed block 41 and the upper feed point 30 which are carried thereby. During the left-to-right movement, the feed 75 point 30 will be separated from the feed block 41 by the action of the cylindrical block 102, which then occupies its upper positions. During the right-to-left movement, the block 102 will lie in the lower 80 portions of the cylindrical opening 100, and the feed point will be spring-pressed into engagement with the feed block, which will thus advance to the fold presser the upper 85 clamped therebetween.

During the left-to-right oscillating movement of the rocking support, while the separated feed point and feed block return to take a new hold upon the stock in preparation for the next forward feed movement, 90 portions of the strip 2 that have previously been wiped are engaged by the plow and by it given an initial fold, as will be clear from Fig. 5. In this figure, the feed elements and the plow are shown as having 95 retraced their movement to the starting point and as about to move forward again, in the direction of the arrow. As the plow is integral with the feed block, it will oscillate with the feeding means. 100

During the backward movement of the feed elements and the plow from the fold presser towards the wiper, the feed point first rises from the full-line position to the dotted-line position of Fig. 11. Then, 105 towards the end of the backward movement, it descends again to the full-line position. During this backward movement, a space is provided between the interior face 28 of the feed point and the plow, allowing the 110 strip in between to become slack or loose. The plow is thus enabled to fold most effectively, without interference from friction by the feed point. The space between the feed point and the plow should be just large 115 enough for this purpose, and neither larger nor smaller. The desired relation between the feed point and the plow may be regulated to some extent by the adjusting screw 138. The position of the pivotal point 110 120 is also important in this connection. This pivotal point should be above the dotted-line position of the interior face 28 of the feed point, as shown, and it should be far enough back so that the feed point shall 125 not rise too high. A slight movement, up and down, of the feed point is all that is necessary. The degree of adjustment of the screw post 120 is therefore another determining factor. The importance of having 130

the parts properly relatively positioned will be understood from a consideration of what will otherwise happen. If the interior face 28 of the feed point is too far away from 5 the plow, the strip and part of the upper to which it is attached will curl over too far towards the left, as viewed in Fig. 8. There will then be a tendency for the line of fold to occur somewhere in the upper 10 near the edge 4, instead of at the proper place in the strip. By suitable design, the feed point and the plow may be made to cooperate to predetermine the fold at just the right line or point. If the feed point 15 travels too high above the plow, it might catch against the top of the strip during its descent and crush it. If the feed point is too close to the plow, the strip may become jammed thereby against the plow and injured. When the feed point and the plow 20 are properly positioned relatively to each other, the feed point, during its descent, will approach the plow at an angle, from the dotted-line position to the full-line position 25 of Fig. 11, to force the strip tightly inward against the plow and to maintain the strip pulled tight during the subsequent feed movement until the feed point again rises preparatory to the next return feed movement. When the feed point rises, the strip 30 is readily released once more, so that it again lies loosely, enabling the plow to fold properly.

The binding strip is maintained in folded 35 position upon the face 16 of the leather by previously applied cement. If the initially folded strip were permitted to contact with the edges 4 and 8 before it has become tightly gripped and pulled tight by the combined action of the feed point and the plow, it would not be possible to pull the strip tight, and the resulting fold would be defective. A separator 143 is therefore provided to maintain the strip separated from the raw edges 4 and 8 until after the feed 40 point and the plow have had an opportunity to pull the strip tight. It is preferred to have the separator situated just in front of the position occupied by the plow on its rearward movement, at a point directly opposite to the position occupied at times by the wiper. The separator is carried upon 45 the end of an arm 145 that is pivoted about a stud 147 mounted on the upper end of the bracket 61. The separator is floating, being maintained yieldingly in the illustrated, active position by a spring 149, but it may be pivotally lifted out of the way, when desired, by pressing down upon a finger 50 piece 151 integral with the arm 145 upon the other side of the pivotal stud 147. The separator 143 is maintained in place between the binding strip and the raw edges 4 and 8 until the forward movement of the 55 feed elements, carrying the stock with them,

causes the separator to be left behind. The binding strip can not, therefore, stick to the edges 4 and 8 before it has been properly folded over.

The upper is advanced by the feed elements and the plow to a diagonally offset edge 144 (Figs. 4 and 5) of the fold presser 42, under which edge the initially plow-folded strip is positioned and by which it is pinched at the very fold. The pinched 70 fold is later pressed into even contact with the face 16 of the upper and over and around the cord 14. This will be further described below. The fold presser is 75 floatingly pivoted at 146, Figs. 3 and 10, to one 80 end of a link 148, the other end of which is eccentrically connected by a pin 150, Fig. 1, to a spiral gear 152 meshing with a spiral gear 154 upon the driving shaft 66. The fold presser, the feeding instrumentalities, 85 the plow and the wiper are thus operated from the same driving shaft in timed relation to one another. The exterior surface of the fold presser is cylindrical, as shown at 156, Figs. 3 and 8, so as to rock within a cylindrical bearing 158 provided at the free end of an arm 160 the other end of which is pivoted at 162. By means of this doubly-pivoted, floating mounting of the fold presser at 146 and 162, its curvilinear 90 working face 164 may be raised from or lowered toward the platform or support 95 24. The curvilinear working face 164 of the fold presser, due to the doubly-pivotal, floating mounting, and the action of the 100 cylindrical bearing 158, descends with a rolling action upon the strip. The previously pinched fold, after it is advanced, on the next feed movement, under the cylindrical face 164, is thus pressed out or rolled 105 over. The rolling action of the fold presser is very important, for it provides for progressively rolling or ironing the strip from the pinched portion of the fold inward 110 towards the unsecured or free edge 26 of the strip, thereby rolling the strip over and around the cord 14 and into even contact with the face 16 of the upper. If the fold presser came down flat, with a single effective blow, it would press the strip across 115 the cord, but not around it. By the above-described mounting, it is possible to set the fold presser very low, so as to enable it to push the strip against, over and around the cord. The fold presser is spring-pressed 120 towards the support 24 by a compression spring 166, Fig. 3, mounted upon a rod 168 extending through an opening (not shown) in the arm 160 and screw-threaded into the frame. By means of the screw threads, the pressure of the spring upon the arm 160 125 may be adjusted, the ends of the spring being confined between the arm and a knurled head 170 upon the rod 168. This construction permits a yielding action of the 130

fold presser upon the strip, relieving the strain thereon, while permitting a positive separation of the fold presser from the strip by the link 148. The yielding tension exerted by the spring 166 from behind the fold presser contributes to the above-described ironing out effect produced by the working face 164, as will be understood from Fig. 10. The working face 164 of the fold presser may be provided with teeth, or may be otherwise roughened, to enable it to secure a firm grip upon the strip at thickened places, such as seams, thereby overcoming the tendency which the fold presser would otherwise have to push the stock away instead of ironing it out.

The retainer 246 presses down upon the stock to prevent the stock being pushed outward away from the operating instrumentalities of the machine; to hold the stock firmly against accidental movement during the return movement of the feed elements; and, cooperating with the wiper, to grip the stock at a point near the raw edge, directly opposed to the point of action of the wiper, and to hold the stock while the wiper performs its wiping action. The preferred retainer is shown bowed out at 248 so as not to obstruct the view of the operator. The retainer 246 is provided with teeth 232, or is otherwise roughened, the more firmly to hold the stock. The retainer presses down firmly, and the wiper wipes, during the return movement of the feed elements. Upon the feed elements resecuring their grip upon the stock, in preparation for another feed movement, the wiper and the retainer release their hold upon the stock, the wiper moving downward, away from the stock as has already been described, and the retainer similarly moving upward. The retainer-operating mechanism will not be described herein, because other retainers may be employed equally well without departing from the scope of the present invention. The details of the operating mechanism of the retainer shown in the drawings of the illustrative machine will be found described in the aforesaid applications.

The preferred wiper is shown provided with teeth of somewhat spiral shape, extending substantially in the direction of movement of the wiper. An end of a spiral tooth first strikes the work, and the remaining portions of the tooth scrape angularly successively over the binding strip during the above-described wiggle movement of the wiper. The action is somewhat the same as that performed by the teeth of a spiral gear. A single tooth upon the wiper, properly positioned and of the proper shape, is probably all that is strictly needed, for its end can grip the binding strip at the place where the latter is secured to the leather and smoothly work its complete length across

the strip during the wiggle movement of the wiper. A plurality of teeth, however, are employed, as illustrated, because it is very difficult to design the one tooth so as to work properly in all machines and under all conditions, and the additional teeth are capable of wiping portions of the binding strip that are missed by the one tooth.

Before the machine is started, it is desirable to raise the feed point from the feed block to permit the insertion of the upper therebetween. A preferred construction for raising the feed point is illustrated in Figs. 1 and 11. The feed point rests upon the screw 123, but is adapted to be raised therefrom through a rod 300 that is vertically disposed in an opening 302 of the rocking support 94. The rod 300 rests upon the head of a rod 304 that is slidably mounted in a vertical opening 306 provided transversely through the rod 96. The rod 304 rests upon one end of a lever 307 pivoted at 308 and that is normally maintained in the illustrated position by a spring 310 coiled about a rod 312. The lower end of the rod 312 is pivotally mounted in a stationary abutment, just behind the abutment 88 shown in Fig. 1 (shown at 314 in Fig. 3 of the drawings of application, Serial No. 407,336). A treadle (not shown) acting upon a link 316, is adapted to actuate the lever 307 so as to cause the raising of the rods 304 and 300 and, through them, of the feed point 30.

The operation of the preferred machine will be better understood from a study of Figs. 5 to 10, which represent the relative positions of the operating instrumentalities of the illustrative machine at spaced points in the cycle of operation. In Figs. 6 and 9, the feed elements are assumed to have reached the end of the forward feed movement. During this feed movement, the retainer and the wiper have both released their hold upon the stock. The fold presser is assumed to be descending to iron out the fold. During the fold-pressing operation, the feed point rises, as is shown more particularly in Fig. 10, releasing its hold upon the material. With the feed block and the plow, it then returns towards the positions illustrated in Figs. 5 and 8. During this return movement, the retainer 246 presses down hard against the stock at a point opposite to the point of operation of the wiper, as above explained. The wiper thus cooperates with the retainer at this time, while the strip is stationary, to wipe or stretch the strip tightly across the edge of the stock, as is shown in Fig. 10a. The action of the wiper diagonal to the strip and oblique to the plane of the sheet has been described above. Very efficient wiping is thus effected, and the stock is not driven directly against the plow, which would cause drag-

ging of the stock against the plow and interfere with feeding the stock. During the return movement of the feed elements, the plow initially folds that portion of the strip over which it rides and which has been previously wiped, as will be clear from the successive positions shown in Figs. 6, 7 and 5. As the plow is rigid with the feed block, it acts also as a gage, thereby additionally helping to predetermine the fold. The substantial distance separating the plow from the wiper, as shown in Figs. 6 and 7, during the return movement of the feed elements, helps the action of both the plow and the wiper. It enables the plow to fold properly without interference from other elements of the machine, which might otherwise drag against the strip; and the wiper could not work at all effectively if the plow were not at some distance away. The wiper is effective during substantially the whole return movement of the plow, and the folding operation of the plow continues until the plow is returned to a point very close to the wiper, as shown in Fig. 5. Towards the end of the return movement of the feed elements, the feed point descends obliquely to the plow, from the dotted-line position to the full-line position of Fig. 11, effecting frictional engagement of the strip between the plow and the interior side face 28 of the feed point, and causing the wiped strip to be pulled tightly in a direction away from the secured-together edges 4 and 8. The action is aided by the use of a sharp projection 33 upon the plow. The feed point and the feed block clamp the material in preparation for the next forward feed movement, Figs. 5 and 8. The feed point and the plow maintain their tight hold upon the strip during the forward feed movement until the feed point again rises, at the end of the feed movement. The preferred wiper acts at closely positioned, isolated points only, while the stock is stationary, during pauses in the feed. The stock is solidly gripped at all times during the forward feed movement, permitting no opportunity for the stock to slip, and the line of fold of the strip about the edges 4 and 8 is absolutely predetermined. The initial, predetermined fold is advanced under the diagonally offset edge of the fold presser, by which it is pinched. The initially pinched fold is, at the next feed movement, brought under the curvilinear working face 164 of the fold presser, by which it is ironed out. The above-described cycle of operations is then repeated. All prior proposals to fold binding strips by machinery have met with failure. The proposals have been of two chief classes: first, to perform all the operations of wiping, folding, pressing and the like in the same machine; and secondly, to perform

some of the operations in one machine or by hand, and the remaining operations in another machine. The difficulties attendant upon the first class of proposals are testified to by the nature 70 and the paucity of the suggestions made, and the impossibility of making the proposed machines work in practice; so much so, in fact, that some manufacturers had come to the definite conclusion that the work 75 could not be accomplished in a single machine. Equally unsuccessful have proved the proposals of the second class, to fold by machinery a binding strip about the edge of the upper to which it is sewed, after the 80 binding strip has first been wiped across the edge of the upper, either by hand or by the use of a second machine. It is essential to the successful operation of the illustrative machine that the wiping, folding, 85 etc., be all performed in the same machine. Hand wiping, for example, is difficult to perform properly. If the wiping is performed by hand or otherwise before the upper is introduced into the machine, furthermore, the machine will be unable to correct the errors of the previous wiping. This is particularly true when, as is usually the case, cement is employed to cause the strip 90 to stick to the upper after it is folded. 95 The cement causes the strip to stick to the upper in its previously wiped condition, resisting the action of the wiper of the illustrative machine, so that the latter can not effect the wiping action properly. If the 100 strip is not wiped tightly to start with, it can not, of course, fold properly.

It will be understood that the invention is not restricted to the exact embodiment thereof that is herein illustrated and described. The invention partakes somewhat of a pioneer character in that it provides not only a new method of folding a binding strip around the edge of the upper to which it is attached, but also, for the first 105 time, successful mechanical means, operable in accordance with the method, for carrying out all the operations connected with the folding of binding strips. Changes and modifications will therefore obviously occur 110 to persons skilled in the art, and those are considered to be embraced within the spirit and scope of the present invention, as defined in the appended claims.

The invention having been thus illustrated and described, what is claimed as new is:—

1. The method of folding a strip around the edge of a sheet of material to one face of which, along the said edge, an edge of the strip is secured so that the sheet and the strip extend from the secured-together edges at an angle to each other, the said method comprising feeding the sheet and the strip, moving portions of the unsecured edge of the strip across the secured-together 125 130

edges when the sheet and the strip are fed to a predetermined position, and folding the moved portions around the secured-together edges when the sheet and the strip are fed to a second predetermined position.

2. The method of folding a strip around the edge of a sheet of material to one face of which, along the said edge, an edge of the strip is secured so that the sheet and the strip extend from the secured-together edges at an angle to each other, the said method comprising feeding the sheet and the strip over a support, wiping successive portions of the unsecured edge of the strip across the secured-together edges when they reach a predetermined position upon the support, folding the wiped portions around the secured-together edges when they reach a second position upon the support, and pressing the folded portions into even contact with the other face of the sheet when they reach a third position upon the support.

3. The method of folding a strip around the edge of a sheet of material to one face of which, along the said edge, an edge of the strip is secured so that the sheet and the strip extend from the secured-together edges at an angle to each other, the said method comprising feeding the sheet and the strip step by step, moving portions of the unsecured edge of the strip across the secured-together edges during pauses in the feed, folding the moved portions around the secured-together edges during pauses in the feed subsequent to the pauses during which they were moved across the secured-together edges, and pressing the folded portions into even contact with the other face of the sheet.

4. The method of folding a strip around the edge of a sheet of material to one face of which, along the said edge, an edge of the strip is secured so that the sheet and the strip extend from the secured-together edges at an angle to each other, a cord being secured to the other face of the sheet along the secured-together edges, the said method comprising wiping the strip tightly across the secured-together edges, folding the strip and pulling it tightly around the secured-together edges, and pressing the strip snugly over and around the cord and into even contact with the said other face of the sheet.

5. A machine for folding a strip around the edge of a sheet of material to one face of which, along the said edge, an edge of the strip is secured so that the sheet and the strip extend from the secured-together edges at an angle to each other, the said machine having, in combination, means for moving the strip across the secured-together edges, means for preliminarily determining a line of fold in the strip and folding the strip

around the secured-together edges along the predetermined line, and means for pressing the folded strip into contact with the other face of the sheet along the predetermined line.

70

6. A machine for folding a strip around the edge of a sheet of material to one face of which, along the said edge, an edge of the strip is secured so that the sheet and the strip extend from the secured-together edges at an angle to each other, the said machine having, in combination, means for moving portions of the unsecured edge of the strip across the secured-together edges, means for folding the moved portions around the secured-together edges, and means for feeding the moved portions from the moving means to the folding means.

7. The method of folding a strip around the edge of a sheet of material to one face of which, along the said edge, an edge of the strip is secured so that the sheet and the strip extend from the secured-together edges at an angle to each other, the said method comprising successively folding successive portions of the unsecured edge of the strip and pulling them tightly around the secured-together edges, pinching the successively folded portions of the strip at the folds against the sheet, and then pressing the successively folded portions of the strip into contact with the other face of the sheet.

8. A machine for folding a strip around the edge of a sheet of material to one face of which, along the said edge, an edge of the strip is secured, so that the sheet and the strip extend from the secured-together edges at an angle to each other, the said machine having, in combination, a support, means for feeding the sheet and the strip over the support, a wiper for wiping successive portions of the unsecured edge of the strip across the secured-together edges when the said portions reach a predetermined position upon the support, means for folding the wiped portions around the secured-together edges when the said wiped portions reach a second predetermined position upon the support, and a fold presser for pressing the folded portions into even contact with the other face of the sheet when they reach a third predetermined position upon the support.

9. A machine for folding a strip around the edge of a sheet of material to one face of which, along the said edge, an edge of the strip is secured so that the sheet and the strip extend from the secured-together edges at an angle to each other, a cord being secured to the other face of the sheet along the secured-together edges, the said machine having, in combination, means for wiping the strip tightly across the secured-together edges, means for folding the strip and pulling it tightly around the secured-together edges, means for preliminarily determining a line of fold in the strip and folding the strip

130

edges, and a fold-presser for pressing the strip snugly over and around the cord and into even contact with the said other face of the sheet.

- 5 10. The method of folding a strip around the edge of a sheet of material to one face of which, along the said edge, an edge of the strip is secured, a cord being secured to the other face of the sheet along the 10 secured-together edges, the said method comprising folding the strip around the secured-together edges, and pressing the strip snugly over and around the cord and into even contact with the said other face 15 of the sheet.

11. A machine for folding a strip around the edge of a sheet of material to one face of which, along the said edge, an edge of the strip is secured, a cord being secured 20 to the other face of the sheet along the secured-together edges, the said machine having, in combination, means for folding the strip around the secured-together edges, and means for pressing the strip snugly 25 over and around the cord and into even contact with the said other face of the sheet.

12. A folding machine having, in combination, a wiper for wiping a strip across 30 the edge of a sheet of material to one face of which, along the said edge, the strip is secured, a plow for folding the wiped strip around the said edge, and means whereby the plow is separated a substantial 35 distance from the wiper when the latter is effective.

13. A folding machine having, in combination, a wiper for wiping a strip across the edge of a sheet of material to one face of which, along the said edge, the strip is secured, means intermittently movable to feed the wiped strip, and a plow movable 40 with the feeding means adapted to fold the wiped strip during the return movement of the feeding means, the wiper being effective 45 during the return movement of the plow until the plow reaches a position close to the wiper, whereby the wiper is effective during substantially the whole return movement 50 of the plow and the plow folds the wiped strip up to a point very close to the wiper.

14. A machine for folding a strip around the edge of a sheet of material to one face 55 of which, along the said edge, an edge of the strip is secured so that the sheet and the strip extend from the secured-together edges at an angle to each other, the said machine having, in combination, means for 60 feeding the sheet and the strip step by step, means for moving portions of the unsecured edge of the strip across the secured-together edges during pauses in the feed, and means for folding the moved portions around 65 the secured-together edges during pauses

in the feed subsequent to the pauses during which they were moved across the secured-together edges.

15. A machine for folding a strip around the edge of a sheet of material to one face of which, along the said edge, an edge of the strip is secured so that the sheet and the strip extend from the secured-together edges at an angle to each other, the said machine having, in combination, means for feeding the sheet and the strip step by step, means for moving portions of the unsecured edge of the strip across the secured-together edges during pauses in the feed, means for folding the moved portions around the secured-together edges during pauses in the feed subsequent to the pauses during which they were moved across the secured-together edges, and means for pressing the folded portions into even contact with the other face of the sheet. 80

16. A folding machine having, in combination, a wiper for wiping a strip across the edge of a sheet of material to one face of which, along the said edge, the strip is secured, a retainer for retaining the sheet against movement acting upon the other face of the sheet, means for folding the strip around the said edge, and means for pressing the strip into even contact with the said other face of the sheet. 90

17. A machine of the class described having, in combination, a wiper for wiping a strip across the edge of a sheet of material to one face of which, along the said edge, the strip is secured, means for feeding the sheet step by step, a retainer for retaining the sheet against movement during pauses in the feed, and means for relatively adjusting the wiper and the retainer. 100

18. A machine of the class described having, in combination, a wiper for wiping a strip across the edge of a sheet of material to one face of which, along the said edge, an edge of the strip is secured so that the sheet and the strip extend from the secured-together edges at an angle to each other, a support for the sheet, means for feeding the sheet and the strip over the support, and a retainer for retaining the sheet against movement, the retainer having a roughened portion, the wiper and the roughened portion being constructed and arranged to act at oppositely disposed points on opposite faces of the sheet. 110

19. A machine of the class described having, in combination, a wiper and a spring-pressed retainer co-operating to wipe a strip across the edge of a sheet of material to which it is secured, the wiper and the retainer being constructed and arranged to act at oppositely disposed points on opposite faces of the sheet. 120

20. A machine of the class described having, in combination, a wiper for wiping a 130

- strip across the edge of a sheet of material to one face of which, along the said edge, the strip is secured, a support for the sheet, means for feeding the sheet and the strip over the support, and a retainer for acting upon the other face of the sheet at a point opposite to the point of action of the wiper during the wiping action of the wiper, the retainer being provided with means for retaining the sheet against displacement by the wiper.
21. A folding machine having, in combination, a wiper for wiping a strip across the edge of a sheet of material to one face of which, along the said edge, the strip is secured, and a plow for folding the wiped portions of the strip around the said edge.
22. A machine for folding a strip around the edge of a sheet of material to one face of which, along the said edge, an edge of the strip is secured so that the sheet and the strip extend from the secured-together edges at an angle to each other, the said machine having, in combination, a wiper for wiping the strip across the secured-together edges, a plow for initially folding the wiped strip around the secured-together edges, and means for pressing the initially folded strip against the other face of the sheet.
23. A machine for folding a strip around the edge of a sheet of material to one face of which, along the said edge, an edge of the strip is secured so that the sheet and the strip extend from the secured-together edges at an angle to each other, the said machine having, in combination, means for feeding the sheet and the strip step by step, a wiper for successively wiping successive portions of the unsecured edge of the strip across the secured-together edges during successive pauses in the feed, means for successively folding the successively wiped portions and pulling them tightly around the secured-together edges during successive pauses in the feed subsequent to the pauses during which they were wiped, and a fold presser for pressing the folded portions of the strip into even contact with the other face of the sheet.
24. A machine for folding a strip around the edge of a sheet of material to one face of which, along the said edge, an edge of the strip is secured so that the sheet and the strip extend from the secured-together edges at an angle to each other, the said machine having, in combination, a wiper for wiping the strip across the secured-together edges, a retainer for retaining the sheet against movement, means for folding the wiped strip around the secured-together edges, and means for pressing the strip into even contact with the other face of the sheet.
25. A machine for folding a strip around the edge of a sheet of material to one face of which, along the said edge, an edge of
- the strip is secured so that the sheet and the strip extend from the secured-together edges at an angle to each other, the said machine having, in combination, means for moving the unsecured edge of the strip across the secured-together edges, means for folding the moved strip around the secured-together edges, and means cooperating with the folding means for pulling the strip tightly around the secured-together edges.
26. A machine for folding a strip around the edge of a sheet of material to one face of which, along the said edge, an edge of the strip is secured so that the sheet and the strip extend from the secured-together edges at an angle to each other, the said machine having, in combination, means for feeding the sheet and the strip, means for moving the unsecured edge of the strip across the secured-together edges, means for folding the moved strip around the secured-together edges and for cooperating with the feeding means to pull the strip tightly around the secured-together edges, and means for pressing the strip into even contact with other face of the sheet.
27. A machine for folding a strip around the edge of a sheet of material to one face of which, along the said edge, an edge of the strip is secured so that the sheet and the strip extend from the secured-together edges at an angle to each other, the said machine having, in combination, a wiper acting intermittently to wipe separated portions of the strip tightly across the secured-together edges, means for intermittently pulling the wiped portions tight and initially folding them around the secured-together edges, means for intermittently feeding the wiped portions from the wiper to the pulling means, and a fold-presser for pressing the initially folded portions into even contact with the other face of the sheet.
28. A machine for folding a strip around the edge of a sheet of material to one face of which, along the said edge, an edge of the strip is secured so that the sheet and the strip extend from the secured-together edges at an angle to each other, the said machine having, in combination, a wiper acting intermittently to wipe spaced portions of the strip tightly across the secured-together edges, a plow for initially folding the wiped portions around the secured-together edges, a fold presser for pressing the initially folded portions into even contact with the other face of the sheet, and means for operating the wiper, the plow and the fold presser in timed relation to one another.
29. A machine for folding a strip around the edge of a sheet of material to one face of which, along the said edge, an edge of the strip is secured so that the sheet and

the strip extend from the secured-together edges at an angle to each other, the said machine having, in combination, a wiper for wiping the strip tightly across the secured-together edges, a separator adapted to lie between the strip and the secured-together edges at a point directly opposite to the wiper, means for folding the strip and pulling it tightly around the secured-together edges, and a fold presser for pressing the strip into even contact with the other face of the sheet.

30. A machine for folding a strip around the edge of a sheet of material to one face of which, along the said edge, an edge of the strip is secured so that the sheet and the strip extend from the secured-together edges at an angle to each other, the said machine having, in combination, means for wiping the strip tightly across the secured-together edges, means for folding the strip after it has been wiped around the secured-together edges, and a floating separator adapted to lie yieldably between the strip and the secured-together edges.

31. A machine for folding a strip around the edge of a sheet of material to one face of which, along the said edge, an edge of the strip is secured so that the sheet and the strip extend from the secured-together edges at an angle to each other, the said machine having, in combination, a feed block, a feed point cooperating with the feed block, a wiper for tightly wiping the strip across the secured-together edges, a plow movable with the feed block between which and the feed point the strip is adapted to be gripped, means whereby the wiped strip is adapted to be gripped between the feed point and the plow, thereby pulling the wiped strip tightly and initially folding the wiped strip around the secured-together edges, a separator adapted to lie between the strip and the secured-together edges at a point directly opposite to the wiper, the plow being adapted to be moved close to the separator on the rearward movement of the feed block, and a fold presser for pressing the initially folded strip into even contact with the other face of the sheet, the plow being adapted to be moved close to the rear portion of the fold presser on the forward movement of the feed block.

32. A machine for wiping a strip across the edge of a sheet of material to one face of which, along the said edge, an edge of the strip is secured so that the sheet and the strip extend from the secured-together edges at an angle to each other, the said machine having, in combination, a rotary shaft having a crank stem disposed at an angle to the shaft, and a wiper for wiping the strip across the secured-together edges mounted upon the crank stem, the wiper being adapted to engage the strip substantially at

points where the strip is secured to the sheet.

33. A machine for folding a strip around the edge of a sheet of material to one face of which, along the said edge, an edge of the strip is secured so that the sheet and the strip extend from the secured-together edges at an angle to each other, the said machine having, in combination, means for moving the strip across the secured-together edges, a separator adapted to lie between the strip and the secured-together edges to separate the strip from the secured-together edges, and means for folding the moved strip around the secured-together edges and for gaging the sheet.

34. The method of wiping a strip across the edge of a sheet of material to one face of which, along the said edge, an edge of the strip is secured so that the sheet and the strip extend from the secured-together edges at an angle to each other, the said method comprising engaging the strip at points where the strip is secured to the sheet, holding the sheet stationary, and wiping the strip diagonally across the secured-together edges from the said points towards the unsecured edge of the strip while the sheet is held stationary.

35. A machine for wiping a strip across the edge of a sheet of material to one face of which, along the said edge, an edge of the strip is secured so that the sheet and the strip extend from the secured-together edges at an angle to each other, the said machine having, in combination, means for feeding the sheet and the strip step by step, and means for engaging the strip at points where the strip is secured to the sheet and, during pauses in the feed, for wiping the strip diagonally across the secured-together edges from the said points towards the unsecured edge of the strip.

36. A machine for wiping a strip across the edge of a sheet of material to one face of which, along the said edge, an edge of the strip is secured so that the sheet and the strip extend from the secured-together edges at an angle to each other, the said machine having, in combination, a wiper for wiping the strip across the secured-together edges, the wiper being adapted to engage the strip substantially at points where the strip is secured to the sheet, and means for bodily actuating the wiper diagonally across the strip from the said points towards the unsecured edge of the strip.

37. A machine for wiping a strip across the edge of a sheet of material to one face of which, along the said edge, an edge of the strip is secured so that the sheet and the strip extend from the secured-together edges at an angle to each other, the said machine having, in combination, a wiper adapted to engage the strip intermittently

- substantially at points where the strip is secured to the sheet, means for intermittently actuating the wiper diagonally across the strip from the said points towards the unsecured edge of the strip, means intermittently movable to feed the unfed strip, and a fold-presser for pressing the initially folded, fed strip into even contact with the other face of the sheet.
- 10 38. A machine for wiping a strip across the edge of a sheet of material to one face of which, along the said edge, an edge of the strip is secured so that the sheet and the strip extend from the secured-together edges at an angle to each other, the said machine having, in combination, a wiper for wiping the strip tightly across the secured-together edges, the wiper being adapted to engage the strip substantially at points where the strip is secured to the sheet, a retainer cooperating with the wiper adapted to engage the other face of the sheet near the said points, and means for actuating the wiper diagonally across the strip from the said points towards the unsecured edge of the strip.
- 15 39. A machine for folding a strip around the edge of a sheet of material to one face of which, along the said edge, an edge of the strip is secured so that the sheet and the strip extend from the secured-together edges at an angle to each other, the said machine having, in combination, a wiper for wiping the strip tightly across the secured-together edges, a plow for initially folding the wiped strip around the secured-together edges, the wiper being adapted to engage the strip substantially at points where the strip is secured to the sheet, and means for actuating the wiper diagonally across the strip from the said points towards the unsecured edge of the strip and away from the plow.
- 20 40. A folding machine having, in combination, a wiper for wiping a strip across the edge of a sheet of material to one face of which, along the said edge, the strip is secured, means intermittently movable to feed the wiped strip, and means for intermittently moving the wiper with the wiped strip as it is fed.
- 25 41. A machine of the class described having, in combination, a wiper, means for wiggling the wiper, and a retainer co-operating with the wiper, the wiper having spiral teeth extending in the direction of the movement of the wiper.
- 30 42. A folding machine having, in combination, a wiper for wiping material, a retainer adapted to clamp the material against the wiper, means for feeding the material, and means whereby the wiper and the retainer release their hold upon the material upon the feeding means commencing to feed the material.
- 35 43. The method of folding a strip around the edge of a sheet of material to one face of which, along the said edge, an edge of the strip is secured so that the sheet and the strip extend from the secured-together edges at an angle to each other, the said method comprising engaging the strip substantially at points where the strip is secured to the sheet, and wiping the strip in a direction oblique to the plane of the sheet across the secured-together edges from the said points towards the unsecured edge of the strip.
- 40 44. A machine for folding a strip around the edge of a sheet of material to one face of which, along the said edge, an edge of the strip is secured so that the sheet and the strip extend from the secured-together edges at an angle to each other, the said machine having, in combination, a wiper adapted to engage the strip substantially at points where the strip is secured to the sheet, and means for actuating the wiper in a direction oblique to the plane of the sheet across the secured-together edges from the said points towards the unsecured edge of the strip.
- 45 45. A machine for wiping a strip across the edge of a sheet of material to one face of which, along the said edge, an edge of the strip is secured so that the sheet and the strip extend from the secured-together edges at an angle to each other, the said machine having, in combination, a wiper for wiping the strip across the secured-together edges, the wiper being adapted to engage the strip substantially at points where the strip is secured to the sheet, and means for wiggling the wiper.
- 50 46. A machine for wiping a strip across the edge of a sheet of material to one face of which, along the said edge, an edge of the strip is secured so that the sheet and the strip extend from the secured-together edges at an angle to each other, the said machine having, in combination, a wiper for wiping the strip across the secured-together edges, the wiper being adapted to engage the strip substantially at points where the strip is secured to the sheet, and means for actuating the wiper across the strip from the said points towards the unsecured edge of the strip in a substantially spiral direction, the wiper having a substantially spiral tooth extending substantially in the direction of movement of the wiper.
- 55 47. A folding machine having, in combination, a fold presser, a wiper, feeding means, and means for actuating the wiper in the line of feed to a position comparatively close to the fold presser.
- 60 48. A folding machine having, in combination, a fold presser, a support against which the fold presser is adapted to press a fold, means for feeding material to the fold

- presser, a separator, and a wiper, the separator being situated at a point opposite to the wiper.
49. A machine of the class described having, in combination, a drive shaft having gear teeth, a shaft having a gear meshing with the drive-shaft gear teeth, a wiper driven from the second-named shaft to wipe intermittently once during each revolution of the shaft, and means permitting adjustment of the gear relatively to the gear teeth to adjust the intermittent wiping action of the wiper.
50. A folding machine having, in combination, a wiper for wiping material, means for actuating the wiper obliquely to and diagonally in the plane of the material, and means whereby successive portions of the wiper are caused to wipe the material during its oblique and diagonal actuation, the said successive portions being adapted to lie in substantially the same plane while wiping.
51. A machine for folding a strip around the edge of a sheet of material to one face of which, along the said edge, an edge of the strip is secured so that the sheet and the strip extend from the secured-together edges at an angle to each other, the said machine having, in combination, means for moving the unsecured edge of the strip across the secured-together edges into substantially the plane of the sheet, means for folding the moved strip around the secured-together edges, a separator adapted to lie between the strip and the secured-together edges at a point opposite to the moving means, and a fold presser for pressing the folded strip into even contact with the other face of the sheet.
52. A machine for folding a strip around the edge of a sheet of material to one face of which, along the said edge, an edge of the strip is secured so that the sheet and the strip extend from the secured-together edges at an angle to each other, the said machine having, in combination, means for moving successive portions of the unsecured edge of the strip across the secured-together edges, a plow for folding the said portion of the strip around the secured-together edges after they have been moved across the secured-together edges by the moving means, a separator adapted to lie between the strip and the secured-together edges just in front of the plow, and a fold presser for pressing the folded strip into even contact with the other face of the sheet.
53. A machine of the class described having, in combination, a rotary shaft having a crank stem disposed at an angle to the shaft, a wiper mounted upon the crank stem provided with a cam shoulder, and means engaging the cam shoulder to maintain the wiper active.
54. A machine for folding a strip around the edge of a sheet of material to one face of which, along the said edge, an edge of the strip is secured so that the sheet and the strip extend from the secured-together edges at an angle to each other, the said machine having, in combination, a wiper for wiping the strip across the secured-together edges, the wiper being adapted to engage the strip substantially at points where the strip is secured to the sheet, a retainer cooperating with the wiper adapted to engage the other face of the sheet near the said points, means for actuating the wiper obliquely to the plane of the sheet, and means whereby the successive portions of the wiper are caused to wipe the material during its oblique actuation, the said successive portions being adapted to lie in substantially the same plane while wiping.
55. A machine for wiping a strip across the edge of a sheet of material to one face of which, along the said edge, an edge of the strip is secured so that the sheet and the strip extend from the secured-together edges at an angle to each other, the said machine having, in combination, a wiper for wiping the strip across the secured-together edges, the wiper being adapted to engage the strip substantially at points where the strip is secured to the sheet, means for bodily actuating the wiper diagonally across the strip from the said points towards the unsecured edge of the strip, and means for folding the wiped strip around the secured-together edges.
56. A machine of the class described having, in combination, a platform having a portion for supporting a piece of work having a concave margin, means for operating upon the work along the concave margin, and means for feeding the work to the operating means over the supporting portion of the platform, the support having a portion inclined to the supporting portion and the inclined portion extending from a position close to the operating means to permit the portions of the work adjacent to the concave margin to bend out of the plane of the work upon the inclined portion while the portions of the work adjacent to the line of bend are maintained substantially unbent.
57. A folding machine having, in combination, a platform having a substantially plane portion for supporting a piece of work having a concave margin, means for folding the work step by step along the concave margin, and means for feeding the work to the folding means step by step over the platform in substantially the plane of the plane portion, the support having a portion inclined to the plane portion and the inclined portion extending from a position close to the folding means to permit the

- move with the material and to fold the edge thereof during the feeding movement, and means whereby the plow completely releases the material during its return movement.
- 5 58. A folding machine having, in combination, a fold presser, intermittently operable means for feeding material thereto, a plow movable with said means adapted to fold the material during the feeding movement, and means whereby the plow completely releases the material during the return movement of the plow.
- 10 59. A folding machine having, in combination, a fold presser provided with an offset edge, a feed block and a feed point intermittently operable to feed material to the offset edge, a plow movable with the feed block and the feed point adapted to fold the material against the feed point during the feeding movement, thereby determining the portion of the material that is to be operated upon by the offset edge, and means whereby the feed block, the feed point and the plow completely release the material during their return movement.
- 15 60. The method of folding material which comprises intermittently feeding material, folding it during the feeding movement, pressing down the fold so formed, and completely releasing the material during the intervals between the intermittent feeding movements.
- 20 61. A folding machine having, in combination, a fold presser, means for advancing material thereto, means for cutting the material with cuts of progressively varying length, and means for variably gaging the material in accordance with the length of the cuts.
- 25 62. A folding machine having, in combination, a fold presser, means for advancing material thereto, and means for cutting the material with cuts of progressively varying length and for variably gaging the material in accordance with the edge contour of the material.
- 30 63. A machine of the class described having, in combination, a plow, means whereby the plow intermittently engages, moves with and folds a piece of material, means whereby the plow intermittently disengages the material and is thereupon retracted, and a fold presser for pressing the folded material.
- 35 64. A machine of the class described having, in combination, means for intermittently feeding material, a plow, means whereby the material is gripped by the feeding means and the plow, means for moving the plow with the feeding means and to cause the plow to fold the material, and means for intermittently separating the plow and the feeding means from the material and for retracting the plow and the feeding means.
- 40 65. A folding machine having, in combination, a fold presser, means for intermittently feeding material thereto, means adapted to engage the material and to move therewith towards the fold presser and fold it during said movement, and means for intermittently retracting said means and to disengage the material during the retraction.
- 45 66. A folding machine having, in combination, a fold presser, a feed point, a plow, means whereby the feed point and the plow grip material and move forward therewith towards the fold presser, means whereby the plow folds the material during the forward movement, and means for separating the feed point and the plow from the material and for retracting the plow and the feed point.
- 50 67. A folding machine having, in combination, a fold presser, a feed point for advancing material thereto, a plow, and means for moving the plow with the feed point to cause one portion of the edge of the material to become folded, and the folded edge gripped, between the feed point and a portion of the plow, and to cause another portion of the folded edge to become further folded between the feed point and another portion of the plow.
- 55 68. A folding machine having, in combination, a fold presser, a feed point for advancing material thereto, a plow having an upstanding portion, and means for moving the plow with the feed point to cause the edge of the material to become folded, and the lower portion of the folded edge to become gripped, between the plow and the feed point, and to cause the upstanding portion to fold the upper portion of the fold against the feed point.
- 60 69. A machine of the class described having, in combination, means for advancing material comprising a feed point and a plow movable therewith adapted to form a fold at a predetermined point in the material, and a curvilinear fold presser adapted to iron out the fold having an offset edge to which the predetermined point is advanced, whereby the offset edge pinches the fold at the predetermined point.
- 65 70. A folding machine having, in combination, an upward and downward moving support for a piece of flexible material, a fold presser, a cutter, an inclined gage, means for feeding the material over the support to the fold presser along the upper portion of the inclined gage out of the path of the cutter when the support is in a lowered position, and means for raising the support to cause the feeding means to feed the material to the fold presser along the lower portion of the inclined gage in a path intersecting the path of the cutter.
- 75 71. A folding machine having, in combination, a fold presser, a plurality of ele-

ments for feeding material to the fold presser, and a block constrained to slide in a diagonal path for operating the feed elements.

5 72. A folding machine having, in combination, a fold presser, means for advancing a sheet of material to the fold presser with the margin folded over upon the sheet, means whereby the fold presser is adapted 10 to engage the folded-over sheet at the edge and margin of the fold only, and means whereby the fold presser is adapted to engage the successive portions of the folded-over portion of the sheet progressively from 15 the edge of the fold inward to progressively press the said successive portions of the folded-over portion from the edge of the fold inward.

73. A folding machine having, in combination, a frame, a knife mounted on the frame, a support removably mounted in the frame, and mechanism for feeding and folding the margin of sheet material mounted in the support and removable with the 25 support.

74. A folding machine having, in combination, a frame, a support pivotally mounted near the rear portion of the frame, folding mechanism mounted upon the support near the front portion of the frame, and means for pivotally actuating the support.

75. A machine of the class described having, in combination, a support, folding 35 mechanism mounted upon the support, means for initially adjusting the support, and means for adjusting the support during the operation of the machine.

76. A folding machine having, in combination, a support having an opening, feed 40 means mounted upon the support, a block slidingly mounted within the opening, means for oscillating and sliding the block to effect a movement of the support, whereby 45 the feed means becomes effective to feed material, means for folding portions of the material, and means for pressing the folded portions.

77. A folding machine having, in combination, means for feeding material, a plow, a fold presser, means whereby the feeding means and the plow are adapted to grip the material intermittently between them and to advance with the material towards the fold 55 presser, and means for separating the plow and the feeding means from the material at the end of each intermittent feeding movement and for thereupon retracting the feeding means and the plow from the fold 60 presser.

78. A folding machine having, in combination, a fold presser having a curved working face, and means for actuating the fold presser to cause the curved working face to 65 engage folded material at the edge and mar-

gin of the fold and to roll progressively over the folded material to press the folded material progressively from the edge of the fold inward.

79. A folding machine having, in combination, a pivoted member, a fold presser having a curved working face pivoted to the member, a portion of the curved face being adapted to engage folded material at the edge and margin of the fold, and power-operated means connected to the fold presser for pivotally actuating the fold presser about its pivotal connection to the member to cause the curved face to roll progressively over the folded material from the edge of the fold inward.

80. A folding machine having, in combination, means for feeding material, means for folding the material, and means for first 85 engaging the folded material at the edge margin of the fold only and for then engaging the folded material progressively from the edge of the fold inward to progressively press the folded material from the edge of the fold inward.

81. A folding machine having, in combination, means for folding the margin of sheet material that is adapted to be fed through the machine, a fold presser having a curved working face a portion of which is 95 adapted to engage the folded margin at the edge and margin of the fold, and means for actuating the fold presser to cause the curved working face to engage the folded margin at the edge of the fold and to roll over the folded margin from the edge of the fold substantially at right angles to the edge of the fold to press the folded margin progressively against the sheet from the edge of the fold inward.

82. A folding machine having, in combination, means for feeding material, a plow for folding the material, a fold presser having a curved working face to which the folded material is adapted to be fed by the 110 feeding means, and means for actuating the fold presser to cause the curved working face to engage the folded material at the edge and margin of the fold and to roll progressively over the folded material to press the folded material progressively from the edge of the fold inward.

83. A folding machine having, in combination, means for feeding material, a plow for folding the material, a fold presser having a curved working face to which the folded material is adapted to be fed by the feeding means, the fold presser having an offset edge adapted to engage the folded material at the edge and margin of the fold, and means for actuating the fold presser to cause the curved working face to roll progressively over the folded material from the edge of the fold inward.

84. A folding machine having, in combi- 130

gaging successive portions of the sheet and the strip at points where the strip is secured to the sheet within the angle between the said one face of the sheet and the strip, 5 a member for engaging successive portions of the margin of the sheet near the said edge along the other face of the sheet at points opposite to the points of action of the first-named member, means for applying pressure to one of the members to cause the said one member to exert a force towards the other member, and means for folding successive portions of the strip around the secured-together edges and pressing them into 10 contact with the said other face of the sheet.

74. A machine for folding a strip around the edge of a sheet of material to one face of which, along the said edge, an edge of the strip is secured so that the sheet and the 15 strip extend from the secured-together edges at an angle to each other, the said machine having, in combination, means for successively preliminarily determining successive portions of a line of fold in the strip and folding the successive portions of the strip around the secured-together edges along the 20 said successive portions of the predeter- 25 mined line, and means for successively pressing the successively folded portions of the folded strip into contact with the other face of the sheet along the predetermined line.

30

75. A machine for folding a strip around the edge of a sheet of material to one face of which, along the said edge, an edge of the strip is secured so that the sheet and the strip extend from the secured-together edges at an angle to each other, the said machine having, in combination, means for preliminarily determining a line of fold in the strip and folding the strip around the secured-together edges along the predetermined line, and means for pressing the folded strip into contact with the other face of the sheet along the predetermined line. 35

76. A machine for folding a strip around the edge of a sheet of material to one face of which, along the said edge, an edge of the strip is secured so that the sheet and the strip extend from the secured-together edges at an angle to each other, the said machine having, in combination, means for successively preliminarily determining successive portions of a line of fold in the strip and folding the successive portions of the strip around the secured-together edges along the said successive portions of the predeter- 50 55 mined line, and means for successively pressing the successively folded portions of the folded strip into contact with the other face of the sheet along the predetermined line. 60

In testimony whereof, I have hereunto subscribed my name this 27th day of February, 1923. 65

ANDREW R. RIDDERSTROM.
